(57) **CLAIM**

The ornamental design for a lid for a container, as shown and described.

DESCRIPTION

FIG. 1 is a perspective view of a first embodiment of a lid for a container showing the new design;

FIG. 2 is a top plan view thereof;

FIG. 3 is a rear elevation view thereof;

FIG. 4 is a front elevation view thereof;

FIG. 5 is a right side elevation view thereof (the left side elevation view is a mirror image of FIG. 5);

FIG. 6 is a bottom plan view thereof;

FIG. 7 is a perspective view of a second embodiment of a lid for a container showing the new design;

FIG. 8 is a top plan view thereof;

FIG. 9 is a rear elevation view thereof;

FIG. 10 is a front elevation view thereof;

FIG. 11 is a right side elevation view thereof (the left side elevation view is a mirror image of FIG. 11);

FIG. 12 is a bottom plan view thereof;

FIG. 13 is a perspective view of a third embodiment of a lid for a container showing the new design;

FIG. 14 is a top plan view thereof;

FIG. 15 is a rear elevation view thereof;

FIG. 16 is a front elevation view thereof;

FIG. 17 is a right side elevation view thereof (the left side elevation view is a mirror image of FIG. 17);

FIG. 18 is a bottom plan view thereof;

FIG. 19 is a perspective view of a fourth embodiment of a lid for a container showing the new design;

FIG. 20 is a top plan view thereof;

FIG. 21 is a rear elevation view thereof;

FIG. 22 is a front elevation view thereof;

FIG. 23 is a right side elevation view thereof (the left side elevation view is a mirror image of FIG. 23); and,

FIG. 24 is a bottom plan view thereof.

(Continued)

The evenly broken lines are shown for the purpose of illustrating parts of the article that form no part of the claim. The dot-dash lines represent the boundaries of the claim and form no part thereof.
